FRONT-BAND CONSTRUCTION FOR FIREARMS

David M. Williams, New Haven, Conn., assignor to Western Cartridge Company, New Haven, Conn., a corporation of Delaware

Application January 3, 1942, Serial No. 425,501

5 Claims. (Cl. 42—75)

The present invention relates to improvements in firearms and relates more particularly to improvements in the construction of the front-band and adjacent elements in firearms of the military type.

One of the objects of the present invention is to provide a superior firearm-structure wherein the front-band is held in place with capacity for ready release and in which the device, coacting with the front-band for releasably retaining the same in place, is in turn retained in place by the front-band proper.

Another object of the present invention is to provide a superior front-band construction for firearms in which there is a minimum amount of unnecessary projections, to thus avoid the tearing of clothing and interference with the free and rapid manipulation of the firearm.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view in side elevation of the forward portion of a firearm equipped with the improved front-band construction of the present invention;

Fig. 2 is an underside view thereof;

Fig. 3 is a broken view of the structure of the preceding figures, with the barrel in side elevation and the stock, barrel-cover and front-band in vertical central-longitudinal section;

Fig. 4 is a transverse sectional view taken on the line 4—4 of Fig. 3 but with the sling-strap omitted;

Fig. 5 is a similar view taken on the line 5—5 of Fig. 3;

Fig. 6 is a broken underside view of the forward portion of the stock detached;

Fig. 7 is a top or plan view of the front-band detached;

Fig. 8 is a view in front elevation of the front-band detached;

Fig. 9 is a view in vertical central-longitudinal section taken on the line 9—9 of Fig. 8; and

Fig. 10 is a perspective view of the front-band retainer detached.

Since the present invention relates only to the portions of firearms adjacent the forward ends thereof, the firearm illustrated in the accompanying drawings shows the forward portion of

a barrel 15 and the similar portion of a stock 16 and barrel-cover or hand-guard 17. As shown, the forward end of the barrel 15 is provided with a sight 18 rigidly secured to the said barrel by a transverse locking-pin 19. Preferably and to insure the accurate alignment of the sight 18, the barrel 15 is provided with an upwardly-and-longitudinally-extending key 20 extending longitudinally along the upper surface of the said barrel and engaged with the sight, as is shown in Figs. 1 and 3.

Slightly to the rear of the front sight 18, a front-band generally designated by the reference character 21 encircles the adjacent portion of the barrel 15. Like the barrel 15 and sight 18, the front-band 21 just referred to is preferably formed of high-grade steel, while the stock 16 and barrel-cover 17 are preferably formed of wood or other suitable heat-insulating material.

The said front-band 21 is formed with a relatively-large-size passage 22 extending therethrough from front to rear and includes a band-like retaining-portion 23 snugly laterally enveloping the adjacent portion of the barrel 15, as is particularly well shown in Fig. 5. In the upper portion of the band-like retaining-portion 23 just referred to, the front-band 21 is formed with a downwardly-opening longitudinal groove 24 designed and adapted to slide over the key 20 of the barrel 15 when the said front-band is being either installed or removed from the firearm during the absence of the said sight 18 from the structure.

The front-band 21 is also provided on its rear upper portion with a rearwardly-extending retaining-lip 25 of substantially-semicircular form crosswise of the front-band and receiving interiorly of itself a similarly-shaped tenon 26 formed on the front end of the barrel-cover or hand-guard 17, as is especially well shown in Fig. 3. Also as is shown in the figure referred to, the said barrel-cover is formed interiorly with a downwardly-opening longitudinal groove 27 of substantially-semicircular form in cross section and providing for the clearance of the upper portion of the barrel 15 and to provide a ventilation passage therearound.

The respective lower edges of the barrel-cover 17 on each of the respective opposite sides of the barrel 15 rest upon the adjacent upper edges of the stock 16. The said stock is formed at its forward end with a tenon 28 projecting forwardly into and through the passage 22 in the front-band 21. The said tenon 28, and a part of the forward portion of the stock 16 proper, is formed

with an upwardly-facing groove 29 of substantially-semicircular form in cross section and shaped to clear the retaining-portion 23 of the front-band 21 and the adjacent portion of the barrel 15. To the rear of its tenon 28, the stock 16 is formed with a deep upwardly-opening longitudinal clearance-recess 30 communicating at its forward end with the groove 29 and providing not only to maintain the adjacent surface of the said stock clear of the barrel 15 but also to lighten the stock 16.

The tenon 26 of the barrel-cover 17, by its projection interiorly of the retaining-lip 25 of the front-band 21, serves to maintain the said barrel-cover 17 against upward displacement relative to the said front-band. In turn, the barrel-cover 17 is prevented from downward displacement relative to the front-band 21 by having the under faces of its respective opposite sides resting upon the upper surfaces of the respective opposite sides of the stock 16 in a plane substantially corresponding to the horizontal center line of the barrel 15. The stock 16 is prevented from downward displacement relative to the front-band 21 by the entry of its tenon 28 into the passage 22 in the said front-band. Conversely, the forward portion of the stock 16 is prevented from upward displacement relative to the front-band 21 by the engagement of the upper faces of its respective opposite sides with the adjacent under faces of the barrel-cover 17.

Since, as above described, the stock 16 and the barrel-cover 17 are stabilized against displacement relative to the front-band 21, it follows that if the front-band itself is stabilized against vertical displacement relative to the barrel 15, the said parts 16 and 17 will, in turn, be held against displacement relative to the said barrel 15. The stabilization of the front-band 21 relative to the barrel 15 is accomplished by the retaining-portion 23 of the said front-band which, in effect, snugly embraces the adjacent portion of the barrel, as is especially well shown in Fig. 5.

For the purpose of holding the front-band 21 against forward displacement relative to the stock 16 and the barrel-cover 17, a front-band retainer 31 is employed (Fig. 10) which is preferably formed of spring-tempered steel. The said retainer 31 includes a cylindrically-contoured stem 32 which upstands from the rear end of the retainer and preferably is integral with a vertically-flexible horizontal arm 33. The arm 33 just referred to, in effect, constitutes the body of the retainer 31, and intermediate its respective opposite ends it is preferably thinned as shown, to give it the desired degree of flexibility in a vertical direction. The front end of the arm 33 of the retainer 31 is formed with an integral head 34 having a rearwardly-facing locking-abutment 35 and an upwardly-and-forwardly-curving under face 36, all for purposes as will more fully hereinafter appear.

The flexible arm 33 of the retainer 31 is accommodated in a longitudinal groove 37 formed in the under face of the tenon 28 of the stock 16. The stem 32 of the retainer 31 is accommodated in a vertical bore 38 formed in the rear portion of the tenon 28 of the stock 16 and communicating in its lower end with the rear portion of the groove 37 and communicating at its upper end with the groove 29 in the upper face of the said tenon, as is especially well shown in Fig. 3.

When installed in the tenon 28 of the stock 16, the retainer 31 has its arm 33 so tensioned as to yieldingly maintain the locking-abutment 35 of

its head 34 in engagement with a forwardly-facing locking-abutment 39. The said locking-abutment 39 constitutes the rear wall of a notch 40 formed in the under portion of the front-band 21 and opening forwardly therefrom, as is especially well shown in Fig. 7.

When the parts are assembled as is especially well shown in Fig. 3, the front-band is prevented from being forwardly displaced relative to the stock 16 and barrel-cover 17 by the rearwardly-facing locking-abutment 35 of the front-band retainer 31. Rearward displacement of the said front-band 21 is prevented by a forwardly-facing shoulder 41 formed on the stock 16 at the rear terminus of its tenon 28, and by a forwardly-facing shoulder 42 formed on the barrel-cover 17 at the rear terminus of its tenon 26. In assembling the structure, it may be noted that after the stock 16 and barrel-cover 17 have been located upon the barrel 15 and the retainer 31 has been assembled with the stock 16, the front-band may be readily slid rearwardly over the tenons 26 and 28 inasmuch as the rear edge of the lower portion of the front-band 21 will engage with the sloping under face 36 of the retainer and automatically flex the arm 33 toward the barrel 15 as the said front-band is slid rearwardly. As soon as the rear face of the front-band 21 is substantially seated against the shoulders 41 and 42 respectively of the stock 16 and barrel-cover 17, the locking-abutment 35 of the retainer will snap down into a position forwardly of the locking-abutment 39 of the front-band 21 to thereby lock the said front-band against forward displacement relative to the structure.

To remove the front-band, the head 34 of the retainer 31 may be pressed toward the barrel 15 to thereby disengage its locking-abutment 35 from the locking-abutment 39 of the front-band 21, whereupon the said front-band may be slid axially forwardly clear of both the stock 16 and barrel-cover 17.

Preferably and as shown, the entire rear portion of the front-band retainer 31 is covered by the front-band 21, and the stem 32 of the retainer is thereby positively prevented from downward movement.

Furthermore, by having the stem 32 or its equivalent of the retainer 31 located in vertical alignment with the front-band 21 and virtually enclosed therein, the stock 16 may be provided with the deep clearance-recess 30 without depriving the retainer of a rugged mount. The virtual envelopment of the rear portion of the retainer 31 and its stem 32 by the front-band 21 or its equivalent, renders the under portion of the stock 16 substantially free of protuberances which would snag upon clothing or the like and interfere with the free manipulation of the fire-arm.

As shown in the accompanying drawings, the front-band 21 is provided on its left side with an integral vertically-extending strap-loop 43 to which is attached the forward end of a sling-strap 44, which however forms no essential feature of the present invention.

The present invention is primarily adapted for use in very light carbines (of five pounds' weight or less) though not so limited. By means of the present invention, not only is the firearm largely streamlined and free of snagging protuberances adjacent the forward portion of its stock, but the front-band retainer may be so light in weight as not to add materially to the weight of the fire-arm. Furthermore, and as before pointed out,

by locating the stem 32 of the retainer 31 in position to be enveloped by the front-band, the stock 16 may have its clearance-recess 30 extended substantially to the tenon 28 to thereby achieve a further economy in weight without depriving the structure of the necessary ruggedness.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A front-band construction for firearms including in combination: a barrel; a stock-member extending adjacent the underside of the said barrel; a barrel-cover member extending adjacent the upper portion of the said barrel; one of the said members being formed with an anchor-socket; a front-band retainer including an anchor-portion extending into the anchor-socket of one of the said members and also including a yielding arm having a locking-abutment engageable with a front-band unit to hold the same against displacement longitudinally of the said barrel; and a front-band unit fitting over portions of each of the said barrel, the said stock-member and the said barrel-cover member, the said front-band unit being constructed and arranged to extend over and substantially conceal the anchor-socket in the said member and the anchor-portion of the said front-band retainer and serving to hold the latter in the said anchor-socket.

2. A front-band construction for firearms including in combination: a barrel; a stock-member extending adjacent the underside of the said barrel; a barrel-cover member extending adjacent the upper portion of the said barrel; one of the said members being formed with a longitudinally-extending recess and with an anchor-socket communicating with the said recess; a front-band retainer including an anchor-portion extending into the anchor-socket of one of the said members and also including a yielding arm located in the longitudinal recess of the said member and having a locking-abutment engageable with a front-band unit to hold the same against displacement longitudinally of the said barrel; and a front-band unit fitting over portions of each of the said barrel, the said stock-member and the said barrel-cover member, the said front-band unit also fitting over and substantially concealing the recess and the anchor-socket in the said member, as well as the anchor-portion of the said front-band retainer and serving to hold the latter in the said anchor-socket.

3. A front-band construction for firearms including in combination: a barrel; a stock extending adjacent the underside of the said barrel and formed at its forward end with a tenon having an anchor-socket therein; a barrel-cover extending adjacent the upper portion of the said barrel; a front-band retainer including an anchor-portion extending into the anchor-socket in the tenon of

the said stock and also including a yielding arm having a locking-abutment engageable with a front-band unit to hold the same against displacement longitudinally of the said barrel; and a front-band unit fitting over portions of each of the said barrel and the said barrel-cover and over the tenon of the said stock, the said front-band unit also fitting over and substantially concealing the anchor-socket in the said member and the anchor-portion of the said front-band retainer and serving to hold the latter in the said anchor-socket.

4. A front-band construction for firearms including in combination: a barrel; a stock extending adjacent the underside of the said barrel and formed at its forward end with a tenon, which latter has a longitudinally-extending recess therein and an anchor-socket communicating with a rear portion of the said recess; a barrel-cover extending adjacent the upper portion of the said barrel; a front-band retainer including an anchor-portion extending into the anchor-socket in the tenon of the said stock and also including a yielding arm located in the longitudinal recess in the tenon of the said stock and having a locking-abutment engageable with a front-band unit to hold the same against displacement longitudinally of the said barrel; and a front-band unit fitting over portions of each of the said barrel and the said barrel-cover and over the tenon of the said stock, the said front-band unit also fitting over and substantially concealing the recess and the anchor-socket in the said member as well as the anchor-portion of the said front-band retainer and serving to hold the latter in the said anchor-socket.

5. A front-band construction for firearms including in combination: a barrel; a stock extending adjacent the underside of the said barrel and formed at its forward end with a forwardly-facing stop-shoulder and with a tenon extending forwardly from the said stop-shoulder, the said tenon being formed immediately adjacent the said stop-shoulder with an anchor-socket and with a longitudinal recess extending forwardly from the said anchor-socket; a barrel-cover extending adjacent the upper portion of the said barrel; and a front-band retainer including a vertically-yielding arm located in the longitudinal recess of the tenon of the said stock and having a locking-abutment engageable with a front-band unit to hold the same against forward displacement, the said retainer being provided at its rear end with an upwardly-projecting stem seated in the anchor-socket in the tenon of the said barrel; and a front-band unit fitting over portions of each of the said barrel and the said barrel-cover and over the tenon of the said stock, the said front-band unit having its rear portion located immediately adjacent the stop-shoulder of the said stock and extending over and substantially concealing the longitudinal recess and the anchor-socket in the tenon of the said stock and also extending beneath the stem of the said retainer to positively prevent the downward displacement thereof.

DAVID M. WILLIAMS.
